UNITED STATES PATENT OFFICE.

WILLIAM D. LYON, OF AKRON, OHIO.

GLARESHIELD.

Application filed July 15, 1922. Serial No. 575,249.

To all whom it may concern:

Be it known that I, WILLIAM D. LYON, a citizen of the United States, residing at Akron, in the county of Summit and State 5 of Ohio, have invented new and useful Improvements in Glareshields, of which the following is a specification.

This invention relates to light projection lamps and has particular relation to a new 10 and improved shield adapted to be secured to the light bulb of such lamps to control and direct the light rays issuing therefrom.

Objects of the invention are to provide a shield of simple, durable construction which 15 may be quickly and conveniently attached to the light bulb of a projection lamp and which in use will provide efficient means whereby a highway may be brilliantly illuminated without producing a glare which 20 will blind pedestrians or other users of the highway.

In view of the discomfort and danger incident to the use of ordinary headlights the most of the States have passed laws against 25 the use of plain lens and lamps for automobile lights and require the provision of some means of avoiding objectionable glare.

Numerous attempts have been made to 30 comply with such laws and provide sufficient illumination for night driving. Many devices have been suggested, but thus far the results have not been wholly satisfactory.

A particular object of this invention is to 35 provide a shield which may be detachably secured to a light bulb of a projection lamp and which when used in connection therewith will permit only indirect rays to issue therefrom.

Another object of this invention is to provide a lamp attachment of the type above 40 indicated which may be easily mounted directly upon the lamp bulb and which will be entirely supported thereby.

Although the device of this invention is 45 highly efficient in operation, it is relatively inexpensive to construct and may be used for an indefinite length of time.

With these and other objects in view, the 50 invention will be more fully described, illustrated in the drawings in which like numerals indicate corresponding parts and then more fully pointed out in the appended claims.

In the drawings:

Figure 1 is a side elevation, partially in

section, of a reflector having a lamp mounted therein provided with a shield constructed in accordance with this invention. 60

Figure 2 is a perspective view of the shield shown in Figure 1.

Figure 3 is a sectional view of a shield mounted upon the lamp, and,

Figure 4 is an end elevation of a lamp 65 having the shield, shown in the previous figures, mounted thereon.

Figure 5 is a side elevational view showing a modification of the invention, and Figure 6 is a central vertical, longitudinal 70 sectional view of same.

In practicing the invention, a lamp shield is constructed by forming a substantially cylindrical body of a suitable sheet metal, the body being provided with a curved end portion and an opening at one side thereof. In order to provide means for mounting the shield upon a lamp, a plurality of gripping fingers are stamped out of the cylindrical member so as to project inwardly therefrom 75 to engage a lamp bulb. In order to increase the efficiency of the device, the interior thereof may be either highly polished or provided with a silver material, such as utilized in reflectors. 80

In order to insure a clear and accurate understanding of my invention, reference may be had to the drawings in which a shield 1 is shown that is constructed in accordance 85 with my invention. As above mentioned, 90 the shield is preferably formed of a suitable sheet metal to provide a substantially cylindrical body having a curved closed end portion 2 provided with a centrally located opening 3. The member 1 is further provided 95 with an enlarged opening 4 at one side thereof to permit of directing light rays from a lamp to a reflector.

The member 1 is designed to be mounted directly upon a lamp. In order to provide 100 means for securing it to a lamp, a plurality of gripping fingers 5 are formed by stamping portions of the member 1 to extend 105 towards the interior of the body. By reason of the fact that the body is formed of sheet metal and a curvature given to the fingers, they possess a certain degree of inherent resiliency, which facilitates mounting the members upon a lamp.

As will be seen upon examination of Figure 1 of the drawing, in order to apply the shield of my invention, it is only necessary 110

to force the fingers over a lamp bulb 6 to clampingly engage it and hold the shield in position. The opening at the side of the member 1 is arranged at the top of the 5 lamp so that any light rays emanating therefrom are directed towards the upper portion of a surrounding reflector 7. It may be desirable to increase the efficiency of the shield by giving the interior of it a highly 10 polished surface or by applying a material to attain the same effect. It will also be observed that the central opening 3 in the curved end of the shield, is adapted to receive the nipple of the lamp and obviates 15 the danger of the lamp being destroyed by being broken at this portion.

In view of the fact that the shield entirely surrounds a lamp, upon which is mounted, with the exception of the opening 20 provided at its side, it is possible to direct all of the rays to any desired portion of a surrounding reflector. As a result, no direct rays are permitted to escape from the lamp and the light that is utilized is directed 25 down upon the highway at a convenient distance from the vehicle upon which it is utilized. Furthermore, the particular means of mounting the shield upon a lamp affords a convenient range of sizes of lamps upon 30 which the shield may be efficiently mounted.

In Figure 4 and Figure 5 there is illustrated an adaptation of the invention in which the reference character 5^a is used to denote a cylindrical body similar to the body 35 1 hereinbefore described and the characters 5^a denote struck-out portions similar to tongues 5. In this modification of the invention the cylindrical body 1^a is provided with a conical end wall 2^a, the numeral 3^a 40 being used to designate an opening similar to the opening 3 hereinafter described.

Although I have shown and described a lamp shield constructed in accordance with my invention, it is obvious that minor 45 changes may be made in the construction and application thereof without departing from the spirit and scope of my invention, and I desire, therefore, that no limitations shall be imposed except such as are indicated in the appended claims.

Having thus illustrated my invention and described the same in detail, what I claim as new and desire to secure by Letters Patent is:—

55 1. A glare shield for head lights, comprising a cylindrical cup adapted to be fitted over an electric light bulb, the cup having a hemi-spherical end wall provided with a centrally positioned opening for the reception of the tip of the bulb, fingers struck

from the wall of said cup, said fingers extending rearwardly and being curved inwardly to engage the bulb to retain the cup thereon, the wall of said cup provided on the upper side thereof with an opening which extends therein from the inner end thereof to a point in spaced relation to the forward wall thereof. 65

2. A glare shield for head lights comprising a cup-like shield of opaque material 70 adapted to be fitted over a light bulb, the forward wall of said shield being provided with a centrally positioned opening adapted to receive the top of the bulb, said shield having an opening in the upper side of its wall, a plurality of fingers struck from said wall, said fingers extending rearwardly and being curved inwardly to engage the bulb and retain the shield thereon. 75

3. In a glare shield for incandescent light 80 bulbs, a cup-like opaque body portion adapted to fit over the bulb, the forward wall of said body provided with a centrally positioned opening adapted to receive the tip of the bulb, the side wall of the body being 85 cylindrical, a plurality of spring fingers struck from said cylindrical wall, said fingers being attached to the wall at points adjacent the forward end thereof and extending rearwardly and inwardly to engage the 90 bulb and retain the shield thereon and a reflecting surface covering the inner face of said body.

4. An automobile lamp shield comprising 95 a cylindrical member having a substantially closed forward end and provided with an opening in its side wall and gripping fingers struck from the wall and projecting inwardly and rearwardly to engage the bulb and retain the shield thereon. 100

5. In combination with a head light, including a reflector having an electric light bulb therein, a shield adapted to be positioned over said bulb, said shield comprising a cylindrical cup, the cup having an outwardly bulged, forward end wall provided with a centrally positioned opening for the reception of the tip of the bulb, spring fingers struck from the wall of said cup, said fingers extending rearwardly and being 105 curved inwardly to engage the bulb and retain the shield thereon, the interior face of said cup being polished to provide a reflecting surface, an opening extending in the upper side of the wall of the cup from the rear 110 edge thereof.

In testimony whereof I have hereunto set my hand.

WILLIAM D. LYON.
